(57) **CLAIM**

The ornamental design for a body surfing board as shown and described.

DESCRIPTION

FIG. 1 is a top, front, and left side perspective view of a body surfing board, embodying my design;

FIG. 2 is a top, rear, and right side perspective view thereof;

FIG. 3 is a front view thereof;

FIG. 4 is a rear view thereof;

FIG. 5 is a right side view thereof, the left side view being a mirror image;

FIG. 6 is a top view thereof; and,

FIG. 7 is a bottom view thereof.

The broken lines depict aspects of the design that form no part of the claimed subject matter.

1 Claim, 7 Drawing Sheets
